Lincoln Johnson
ATTORNEY

UNITED STATES PATENT OFFICE.

CLEMENCE FRANCK, OF SAN FRANCISCO, CALIFORNIA; MILTON FRANK ADMINISTRATOR OF SAID CLEMENCE FRANCK, DECEASED, ASSIGNOR TO CAROLYN CONRADI, OF SAN FRANCISCO, CALIFORNIA.

POWDER PUFF.

Application filed January 30, 1928. Serial No. 250,432.

This invention relates particularly to powder puffs.

An object of the invention is to provide a powder puff out of powder permeable material, with a mouthpiece on the said puff to fill or discharge powder thereinto or therefrom, said mouthpiece being concealable within the puff when not being used for powder filling purposes.

10 A further object of the invention is to provide a metal clasp for powder puffs comprised of a pair of complementary parts adapted to be maintained in matching relationship over a powder filling inlet in a powder puff, said clasp being collapsible to permit the entry of powder into the puff and locked and tucked into a position within the puff to prevent any parts of the metal clasp from coming into contact with surface to which 20 the puff may be applied, to prevent injury.

Other objects of the invention are to provide a powder puff and clasp therefor that will be superior in point of simplicity, inexpensiveness of construction, positiveness of 25 operation, and facility and convenience in use and general efficiency.

In this specification and the annexed drawings, the invention is illustrated in the form considered to be the best, but it is to be understood that the invention is not limited to such form, because it may be embodied in other forms; and it is also to be understood that in and by the claims following the description, it is desired to cover the invention 35 in whatsoever form it may be embodied.

In the accompanying one sheet of drawings:

Fig. 1 is a front elevation of a powder puff having a clasp thereon constructed in 40 accordance with my invention, said view being broken away to show the manner of tucking the clasp within the puff.

Fig. 2 is a vertical section taken through Fig. 1 on the line 2—2.

45 Fig. 3 is an enlarged front view of one of the clasps for the filling vent in the powder puff.

Fig. 4 is a cross section taken through Fig. 3 on the line 4—4.

50 Fig. 5 is a plan view of one of the metal clasp blanks before being formed into the desired shape.

In detail the construction illustrated in the

drawings comprises a pair of complementary sheets of powder permeable fabric material 55 1 and 2, such as woolen sheeting, or other soft finished goods, cut into any desired fanciful shape, but, preferably incorporating therein a plurality of small diametered circular contours 3, which may be effectively used in applying the puff to all parts of an irregular surface, such as the human face and to provide a more attractive effect; as will be hereinafter explained in detail. The sheets 1 and 2 are stitched together around the bounding 60 edges thereof and said edges are suitably scalloped or otherwise treated to present a decorative exterior. The sheets may be sewed together in the manner shown or joined in some other conventional manner. 70

The sheets 1 and 2 are provided with two relatively long opposite sides 4 and 5, which taper to a relatively narrow apex 6. The edge of the sheets across the apex is not sewed but is left open to permit access to be had into the 75 space between the sheets. The unstitched opening in the apex provides a filling vent or inlet through which powder is filled into the puff.

The opening in the apex is closed by a two 80 part clasp preferably formed of a light weight metal. The clasp comprises two complementary halves 8 and 9 each being a duplicate of the other. Each clasp is stamped and formed by the same die operation and each clasp consists of a metal blank having a serrated bottom edge 10, and notched ends 11 and 12. The serrations in the bottom edge are adapted to be folded over and inserted into the material on one side of the filling vent. 90 When each clasp is properly positioned, in facing relation on each of the opposite sides of the filling vent, the serrations are given a final bending to firmly hold the fabric material against the body of the clasp. The two 95 facing clasps will thus lie parallel to each other and parallel with the plane of the sheets 1 and 2 and extending outwardly from an edge thereof.

An elastic band 14 is then stretched around the facing clasps 8 and 9 engaging the notches 11 and 12 at the ends of said clasps, to thus position the band 14 in position thereon and to hold the clasp halves together. The elastic band is preferably allowed to engage the 105 clasps 8 and 9 in the manner shown, as by so

doing it exerts sufficient tension to hold the clasp halves closed and to prevent any powder held within the puff from spilling. The band 14 may also be quickly and easily removed to 5 allow the clasp halves to be separated and the puff vent to be opened for the purpose of charging the powder interior with powder.

The clasp halves are placed in the position shown in Fig. 1 when the puff is to be filled 10 with powder. Thereafter, the sheets 1 and 2 are separated a sufficient distance to permit the narrow neck piece of the puff, together with the metal clasp, to be depressed or tucked down into the puff between the outer halves 15 thereof, as shown by dotted lines in Fig. 1. When the metal clasp is concealed within the puff it is out of the way so that it cannot contact with any surface that the puff may be passed over, yet it is sufficiently accessible for 20 filling purposes. The manner of tucking the metal clasp into the puff, squares off one side of the puff and forms two corners which are very handy for applying powder into relatively small depressions in the face. The puff, 25 with the filling neck extended, is from one-third to one-half larger than when the neck and clasp are tucked within the puff in readiness for use as a powder puff.

The elastic band or other equivalent clasp holding means, may be allowed to pass around the clasps, as shown, or sewed or otherwise suitably attached in a semi-permanent position to the puff material, by continuing the bag stitching to form a thread link.

35 Having thus described this invention, what I claim and desire to secure by Letters Patent is:

1. A powder puff comprised of a fabric container to contain powder; and an extensible mouth piece on said container through which powder is filled into the container adapted to be concealed within the container when not being used for filling purposes, said container having the two edges thereof on opposite sides of the mouth piece tapered outwardly to permit the said mouth piece to be tucked into the container.

2. A powder puff comprised of a powder permeable container; and a metal mouth piece on the container through which the container is filled with powder adapted to be tucked into a concealed position in the container to prevent contact of the mouth piece with any surface to which the container might be applied, said container having the two edges thereof on opposite sides of the mouth piece tapered outwardly to permit the said mouth piece to be tucked into the container.

3. A powder puff comprised of a fabric container having an inlet for powder therein, two of the opposite sides of said container tapering outwardly from the inlet; and a separable clasp, engaging the container on opposite sides of the inlet to prevent the entry or discharge of powder into or from the con-

tainer, adapted to be tucked into a concealed position within and between the tapered sides of the container.

4. A powder puff comprised of a fabric container having an inlet for powder therein, 70 two of the opposite sides of said container tapering outwardly from the inlet; a separable clasp, engaging the container on opposite sides of the inlet to prevent the entry or discharge of powder into or from the container, 75 adapted to be tucked into a concealed position within the tapered sides of the container; and means to hold the separable clasp in a locked position.

5. A powder puff comprised of a fabric 80 container having an inlet for powder therein, two of the opposite sides of said container tapering outwardly from the inlet; a separable clasp, engaging the container on opposite sides of the inlet to prevent the entry or discharge of powder into or from the container, 85 adapted to be tucked into a concealed position within the tapered sides of the container; and a resilient strap encircling the clasp to hold it in a closed position. 90

6. A powder puff comprised of a powder permeable container having an opening in an edge thereof, two of the opposite sides of said container tapering outwardly from the opening, a metal clamp engaging the container 95 on each of the opposite sides of the opening; and means to hold each of the clamps locked together to prevent the discharge of powder from the container through the inlet therein, said metal clamp being concealable within the tapered sides of the container when not being used for filling purposes to prevent contact of the metal parts to any surface to which the container might be applied. 100

7. A powder puff comprised of a powder 105 permeable container having an opening in an edge thereof, two of the opposite sides of said container tapering outwardly from the opening, a metal clamp engaging the container on each of the opposite sides of the opening; and a resilient strap encircling the clamps to hold each of the clamps locked together to prevent the discharge of powder from the container through the inlet therein, said metal clamps being concealable within the tapered 110 sides of the container when not being used for filling purposes to prevent contact of the metal parts to any surface to which the container might be applied. 115

8. A powder puff comprised of a pair of 120 matching fabric sheets secured together around substantially the entire edges thereof, to form a container for powder, there being an unstitched portion along the sheet edges to provide an opening into the space between the sheets; two of the opposite sides of said container tapering outwardly from the opening, a metal clamp engaging each of the opposite sheets in facing relation on opposite sides of the opening, said clamps extending 125 130

from the sheet edges in a plane parallel therewith; resilient means to hold each of the clamps together to prevent the escape of powder from the container, said metal clamps 5 when locked being adapted to be tucked into a concealed position within the tapered insides of the sheets to prevent the metal parts

from contacting with any surface to which they might be applied.

In testimony whereof, I have hereunto set 10 my hand at San Francisco, California, this 24th day of January, 1928.

CLEMENCE FRANCK.
